FASTENING FOR SECURING RAILWAY RAILS TO METAL SLEEPERS

Filed Feb. 21, 1948

UNITED STATES PATENT OFFICE

2,568,376

FASTENING FOR SECURING RAILWAY RAILS TO METAL SLEEPERS

**William B. Wragge, Stockport, England, assignor
to executors of James Mills, Limited, Woodley,
near Stockport, England.**

**Application February 21, 1948, Serial No. 10,015
In Great Britain November 13, 1946**

Section 1, Public Law 690, August 8, 1946
Patent expires November 13, 1966

8 Claims. (Cl. 238—364)

This invention has reference to fastenings for securing flat- or flange-footed railway rails to metal sleepers and to such fastenings comprising a substantially U- or C-shaped clip, one limb of the clip constituting a hook-like tail adapted to be hooked into a hole in the sleeper to engage its end below the latter, and the other limb constituting a jaw which lies above the sleeper and between which and the foot or flange of the rail a key is driven to secure the rail on the sleeper.

It is already known to produce a blank of substantially T-shape from flat strip or sheet steel and by pressing operations fashion or bend the blank to form a clip as aforesaid, the cross member of the blank forming the jaw of the clip and the stem of the blank forming the hook-like tail. It is also known to produce the blank from strip material having a central longitudinal rib or bead in such manner that the rib or bead lies on the rear face or back of the blank and extends centrally across the cross member and along the stem to the end of same. This rib or bead correspondingly increases the thickness, and adds considerably to the strength of the tail of the finished clip. The rib or bead also provides a central area of increased thickness in the length of the jaw of the clip which increases the strength or stiffness of the jaw. The rib or bead has the disadvantage, however, of increasing the weight, and hence the cost, of the clip, as compared with one fashioned from a blank of flat material.

The object of this invention is to provide an improved clip having in the tail, and if desired also in the jaw, the advantage of increased strength comparable with that afforded by the aforesaid rib or bead without the attendant disadvantages of added weight and cost.

According to the invention the hook-like tail of a clip of the kind referred to is made of more or less U, V or other grooved trough or channel section which section may at the root of the tail merge into the jaw or may extend partly across the jaw and then merge therewith or may extend completely across the jaw to the upper longitudinal edge thereof.

The invention is hereinafter further described with reference to the accompanying drawings in which

Fig. 1 is a transverse section of a railway rail secured on a metal sleeper by means of one form of clip fastenings in accordance with the invention.

Fig. 2 is a perspective view to a larger scale of one of the clip fastenings shown in Fig. 1 and

Figs. 3, 4, 5 and 6 are perspective views of modified forms of clip fastenings according to the invention.

Fig. 7 is a sectional view, a horizontal section being taken on line 7-7 of Fig. 1; and Fig. 8 is a sectional view, a vertical section

Fig. 6 is a sectional view, a vertical section being taken on line 8-8 of Fig. 1.

On the drawings and in the following description like numerals of reference indicate like parts.

Referring to Fig. 1 of the drawings, 7 is the rail and 8 is the sleeper upon which the rail is mounted and secured by means of clips 9 and keys 10. The clips are of more or less U- or C-shaped profile comprising lower and upper limbs 11 and 12, respectively. The lower limb 11 of the clip constitutes a hook-like tail which is passed through a hole 13 in the sleeper 8 to engage below the part 14 thereof adjacent the hole 13. The upper limb 12 of the clip comprises a jaw 12' which lies above the sleeper and in between which and the foot 15 of the rail 7 the key 10 is driven, the key having a jaw engaging surface 20 shaped to the contour of the jaw 12 and a flange engaging surface 21 for engaging the corner of the rail foot 15.

30 The clip 9 exemplified in Fig. 1 can be readily and cheaply manufactured by first producing a substantially T-shaped blank of flat material and pressing the blank between appropriate dies to form the clip, shown better in Fig. 2, having the tail 11 of grooved or channeled trough section 16 which section extends from the tip of the tail right across the jaw 12' to the upper longitudinal edge 17, thus producing spaced bearing surfaces 22, 23 and 24, 25 at the jaw portion and at the tail portion, respectively. Alternatively, the grooved or trough section may be formed in the blank beforehand by producing the blank from 35 material rolled with a groove or corrugation which in the blank extends centrally across the cross member and along the stem, and pressing the blank in dies to fashion it into the finished clip.

45 Fig. 3 illustrates a clip of heavier type than that shown in Figs. 1 and 2 and produced by forging or other operations. In this case, as before, the tail 11 of the clip is of grooved or trough section and the channel 16 extends across the jaws to the longitudinal edge 17.

In the clips shown in Figs. 2 and 3 the inner profile of the groove or trough section 16 is curvilinear but if desired the section may be flat 55 sided, for example it may be of more or less V-

shape. Or the section may be flat bottomed as exemplified in Fig. 4.

The grooved, trough or channel section 16 may be uniform throughout or it may vary in depth and/or width between the tip of the tail 11 and the longitudinal edge 17 of the jaw 12. Fig. 5 shows a clip of still heavier type, produced by forging operations, in which the groove or trough 16 gradually increases in depth and width from the longitudinal edge 17 of the jaw 12' to the tip of the tail 11.

The tail 11 of the clip may be uniform or vary in width and/or depth.

Fig. 6 illustrates a clip in which the jaw 12' is formed without wings extending from each side of the groove or channel section 16 such as the clips shown in Figs. 1 to 5 are provided with. In this case the edges of the walls or sides of the groove or trough section 16 are formed with beads 18 which afford additional strength and constitute the spaced bearing surfaces 22, 23 and 24, 25.

In all cases the bottom of the groove or trough which separates the bearing surfaces will when the clip is fitted in position decline to the tip of the tail 11 in order that water which may gain access into the section may drip therefrom and not be trapped to set up corrosion, as is shown in Fig. 1.

I claim:

1. A clip for securing the flange of a rail to a metal sleeper by means of a wedging key interposed between the flange and the clip, the clip having a body substantially C-shaped in profile, the body comprising an upper head portion engaged by the key and a lower tail portion extending through an aperture in the sleeper to engage the underside of the sleeper, characterized in that at least the tail portion is of channeled cross section, whereby two bearing surfaces are provided at the concave side of the C, spaced longitudinally with respect to the rail, at which the tail portion engages the sleeper, the channeled portion extending to a point above the sleeper, considering the clip in installed position, the convex side of the C being of continuous curvature.

2. A clip for use in securing the flange of a rail to a metal sleeper by means of a wedging key interposed between the flange and the clip, the clip having a body substantially C-shaped in profile, the body comprising an upper head portion engaged by the key and a lower tail portion extending through an aperture in the sleeper to engage the underside of the sleeper, characterized in that the body is of channeled cross section providing in both the head portion and in the tail portion pairs of spaced bearing surfaces at the concave side of the C at which the clip engages the wedging key, and the undersurface of the sleeper, respectively, the bearing surfaces of each pair lying on opposite sides of the channel thus formed and being spaced by said channel which provides a non-bearing central relief area between the bearing surfaces of each pair, the curvature of the clip along the convex side of the C, extending from the head portion to the tail portion, being continuous.

3. A clip for use in securing the flange of a rail to a metal sleeper by means of a wedging key interposed between the flange and the clip, the clip having a body substantially C-shaped in profile, the body comprising an upper head portion engaged by the key and a lower tail portion extending through an aperture in the sleeper to engage the underside of the sleeper, characterized in that the body is of channeled cross section

providing in both the head portion and in the tail portion pairs of spaced bearing surfaces at the concave side of the C at which the clip engages the wedging key and the undersurface of the sleeper, respectively, the bearing surfaces of each pair lying on opposite sides of the channel thus formed and being spaced by said channel which provides a non-bearing central relief area between the bearing surfaces of each pair, the curvature of the clip along the convex side of the C, extending from the head portion to the tail portion, being continuous, said head portion being provided with wings extending laterally beyond the width of the tail portion, the surface of said wings facing the concave side of the C being continuous with the bearing surfaces of the head portion.

4. A clip for use in securing flanged rails to metal sleepers, the clip having a body substantially C-shaped in profile, the body comprising a head portion, and a tail portion which lies below the head portion, the head portion and the tail portion having bearing surfaces on the concave side of the C profile, the body further providing a bearing surface intermediate the head and the tail portions for engagement with the edge of an aperture in the sleeper, the latter bearing surface being on the convex side of the C profile, the convex side being of continuous curvature at, above, and below, said latter bearing surface, at least the tail portion of the body being of channeled cross-section, the channel being open towards the concave of the C and the concave side of the C having flush engagement with the underside of the sleeper along that part of the tail portion which lies below and in contact with the underside of the sleeper.

5. In a railway rail fastening assembly comprising the combination of a metal sleeper, a rail, a clip securing the flange of the rail to the sleeper, a wedging key interposed between the flange and the clip, said sleeper having an aperture therein, the clip having a body substantially C-shaped in profile, the body comprising an upper head portion engaged by the key and a lower tail portion which extends through said aperture in the sleeper and engages the under side of the sleeper, the provision of such clip which is characterized in that at least the tail portion is of channeled cross section, whereby two bearing surfaces are provided at the concave side of the C, spaced longitudinally with respect to the rail, at which the tail portion engages the sleeper, the channeled portion extending to a point above the sleeper, the convex side of the C being of continuous curvature, and the concave side of the C having flush engagement with the underside of the sleeper along the entire length of the tail portion which is below such under side of the sleeper.

6. In a railway rail fastening assembly comprising the combination of a metal sleeper, a rail, a clip securing the flange of the rail to the sleeper, a wedging key interposed between the flange and the clip, said sleeper having an aperture therein, the clip having a body substantially C-shaped in profile, the body comprising an upper head portion engaged by the key and a lower tail portion which extends through said aperture in the sleeper and engages the under side of the sleeper, the head portion and the tail portion of said body having bearing surfaces on the concave side of the C profile, the body further providing a bearing surface intermediate the head and the tail portions which

engages with the edge of the aperture in the sleeper, the latter bearing surface being on the convex side of the C profile, the convex side being of continuous curvature at, above, and below, said latter bearing surface, at least the tail portion of the body being of channeled cross-section, the channel being open towards the concave of the C, and the concave side of the C having flush engagement with the under side of the sleeper along the entire length of the tail portion which is below such under side of the sleeper.

7. A clip for use in securing flanged rails to metal sleepers, the clip having a body substantially C-shaped in profile and of channeled cross section, the channel thus formed being open towards the concave side of the C, the body comprising a head portion and a tail portion which lies below the head portion when the clip is considered in installed position, the head portion and the tail portion each having pairs of bearing surfaces on the concave side of the C profile, the surfaces of each pair lying on opposite sides of, and being spaced by, said channel which provides a non-bearing central relief area between the bearing surfaces of each pair, the body further providing a bearing surface intermediate the head and the tail portions for engagement with an edge of an aperture in the sleeper, the latter bearing surface being on the convex side of the C profile, the convex side being of continuous curvature at, above, and below said latter bearing surface, considering the clip in installed position.

8. A clip for use in securing flanged rails to metal sleepers, the clip having a body substantially C-shaped in profile and of channeled cross section, the channel thus formed being open towards the concave side of the C, the body com-

prising a head portion and a tail portion which lies below the head portion when the clip is considered in installed position, the head portion and the tail portion each having pairs of bearing surfaces on the concave side of the C profile, the surfaces of each pair lying on opposite sides of, and being spaced by, said channel which provides a non-bearing central relief area between the bearing surfaces of each pair, the body further providing a bearing surface intermediate the head and the tail portions for engagement with an edge of an aperture in the sleeper, the latter bearing surface being on the convex side of the C profile, the convex side being of continuous curvature at, above, and below said latter bearing surface, considering the clip in installed position, the head portion being provided with wings extending laterally beyond the width of the tail portion, the surface of said wings facing the concave side of the C being continuous with the bearing surfaces of the head portion.
